UNITED STATES PATENT OFFICE.

ALOIS TSCHERNE, OF RORSCHACH, SWITZERLAND.

MACHINE FOR CUTTING EMBROIDERY.

1,359,770.

Specification of Letters Patent. Patented Nov. 23, 1920.

Application filed September 3, 1919. Serial No. 321,413.

To all whom it may concern:

Be it known that I, ALOIS TSCHERNE, a citizen of the Swiss Confederation, and residing at Rorschach, Switzerland, have invented certain new and useful Improvements in Machines for Cutting Embroidery, of which the following is a specification.

The present invention has reference to certain new and useful improvements in machines for cutting embroidery, and it relates more particularly to a machine having two superposed revoluble disk knives for cutting the fabric along the edge of embroidery and means in connection with the fabric feeding mechanism for so controlling the fabric feed that it is dependent upon the direction of the embroidery edge, making thereby the feed elastic in keeping with the cutting resistance and speed, an arrangement which effectively protects fabric and embroidery against injury.

My invention will best be understood when described in connection with the accompanying drawings, in which Figure 1 is a front elevation of the new cutting machine, with parts in section or broken away; Fig. 2 is a top view with the work table removed; Fig. 3 is a side view; Fig. 4 represents a plan of a part of the machine; Fig. 5 is a side view of Fig. 4; Fig. 6 shows a detail, of which Fig. 6^a shows a partial plan, and Fig. 7 illustrates diagrammatically the operation of the machine.

From the bed plate 1 rises the standard 2 supporting sleeves 3 and 4 in which are respectively journaled the shafts 7 and 8 to the upper extremities of which are fixed the circular cutting tools 5 and 6, which hereinafter will be referred to simply as knives. These shafts 7 and 8, and thus also the knives, are driven by a flexible member 14, for instance of catgut, in relatively opposite direction, the catgut 14 passing over circumferentially channelled wheels 12 and 13 respectively, the one of which is fixed to the shaft 11 and the other one of which turns loosely on this shaft, which latter is rotatably journaled in the bearings 9 and 10 respectively. The shaft 11 is driven in any suitable manner over its fixed pulley 15, for instance by a not shown electromotor or other source of power. The knives 5 and 6 are in the shape of co-operating, rotatable, disk-like edge tools, and are so arranged that they partially overlap, so that their

planes 5' and 6' meet at a point *a* (Fig. 6^a), their peripheries then constituting a cutting device in the manner of a rotary shears. The point of contact *a*, the cutting point, faces the work table T over which the work piece to be cut is fed.

From the support sleeves 3 and 4 respectively extend brackets 3' (Fig. 1) and 4' (Fig. 5) which support guide or gate members 16 and 17 respectively, which form between them immediately in front of the fabric intake or cutting point *a* the intake slit or gate E (Figs. 2 and 4) which is vertically directed relative to the middle plane of the knives and which is designed to admit solely the ground fabric but not the embroidery portion, so that the knives can act only on the fabric but not on the embroidery edge. The gate member 16 is rigid, while the member 17 can be horizontally 75 securably displaced in suitable manner, so that the width of the gate E can be adjusted to fit any thickness of fabric.

For advancing the fabric there are arranged two pairs of rollers 19, 20 (Figs. 1 and 2) and 21, 22 (Figs. 2 and 4), the former roller pair serving for drawing down the waste portion and the latter for acting on the embroidered portion. The roller pair 19, 20 is driven by means of a worm 23 fast on the shaft 11, which meshes with a worm wheel 24 fast on a shaft 26 which is journaled in the bearing sleeve 25 (Fig. 2). This shaft 26 also carries the driving wheel 27 which meshes with the driving wheel 28 fast on the roller shaft 19'. On the shaft 26 rides loosely the outrigger member 29 with cross-sleeve 30, in which latter the one end of the shaft 19' is journaled. The outrigger further is provided with a downcranked arm 29' (Fig. 1) to which is pivotally secured the lever 31 journaling the shaft 20' of the roller 20. The two rollers thus can rock about the shaft 26. The spring 32 acting on the upper end of the lever 31 tends to press the roller 20 against the roller 19, and both rollers can rotate freely. The roller 19 is arranged between the fixed disk 33 (Fig. 2) and the axially shiftable pressure disk 34, which is secured to the narrow sleeve 37 supported on the fork member 35 and is adapted to be axially displaced on the shaft 19' against the action of a spring 36. According as this spring 36 forces the sleeve 37 and thus 110

also the disk 34 against the roller 19, the latter will be pressed more or less forcibly against the rigid disk 33, and thus the roller will be rotated at a correspondingly greater or lesser speed, all of which is caused by the more or less pronounced pressure of the fabric against the gate members 16 and 17. The fork 35 is pivoted to a lever arm 38 which is rockingly supported by means of pivot screws 40 in a support member 39. This latter is rotatably journaled by its trunnion 41 in an upstanding bearing member 42, the whole presenting a kind of universal joint which permits of the rocking axis of arm 38 assuming different angular positions relative to the horizontal. By this relative angular displacement the lever 38 and the fork 35 linked thereto can be subjected to lateral displacement so that on the lever 38 with its roller 19 swinging upwardly, the fork 35 will swing outwardly, which forces the sleeve 37 and thus the pressure disk 34 away from the roller against the action of the spring 36, and on the lever 38 with the roller swinging down into the lowermost position fixed by a stop 30', the fork will swing inwardly, allowing the spring to press the pressure disk 34 against the roller 19. Thus on the roller 19 swinging up there will be a corresponding retardation in its rotary speed. The roller 19 also can be arrested completely when the ascending end K' of the edge of the embroidery, for instance a festoon F (Fig. 7) is drawn against the gate members 16 and 17 and is about to be cut, when, owing to the resistance occasioned by the edge, there is danger of the fabric being torn. But this danger is effectively neutralized by the reduction of the feed speed or the momentary arrest of the rollers, when the pull on the fabric is correspondingly eased, the latter always being held under a tension corresponding to the obtaining resistance.

This arrangement serves to automatically control the feed of the work piece through between the roller pairs 19, 20 and 21, 22, by so regulating the actuation of the latter under the influence of the resistance opposed to the cutting by the embroidery edge, that the rollers alternately cause the one or the other fabric portion to act more or less forcibly against the gate members or the knives respectively, so that the embroidery is always drawn through the knives with the momentarily required degree of pull.

This pull, obviously, must be weak when the ascending end of the embroidery edge K' is being cut, and it is caused by the rollers 19, 20; it is to be strong when the descending edge K'' is being severed, in which instance the roller pair 21, 22 is pulling.

To a pin 43 extending from the outrigger 29 (Fig. 5) is secured one end of the spring

44 whose other end is secured to a screw stud which is supported in an upstanding arm 47 and can be relatively adjusted by the set screw 45, this spring then regulating the swing-movement of the roller pair 19, 20.

The roller pair 21, 22 is driven from the shaft 26 by means of the bevel gears 48, 48' (Fig. 3), 49, 50, 51 and 52 (Fig. 2). The wheel 52 is fast on the shaft 54 as is also a coupling member 53, while the supplemental coupling member 55 and the roller driving wheel 56 ride loosely on this shaft 54 with capability of axial displacement thereon. On the roller 21, which is arranged above the shaft 54, there is provided a wheel 57 which meshes with the wheel 56 (Fig. 3). The roller 22 is located above the roller 21 and is frictionally taken along thereby, as is also the case with the rollers 19 and 20. The roller 22 is journaled on trunnions 60 in a frame or yoke member 58 (Fig. 3) which by means of a pin 59 is pivotally suspended from a bracket member 61, which latter is hinged to a fixed machine part and can readily be laid over.

The coupling member 55 is connected to an annular slide 62 with which coöperates a fork 63 fixed on the one end of a shaft 66 which is rotatably journaled in the bearings 64 and 65. The other end of the shaft 66 carries a lever 67 to which is secured the one end of a draw rod 68 (Fig. 3), whose other end is connected to a pin 69 secured to an arm 70 extending from the outrigger member 29, the draw rod being connected to the lever 67 and to the pin 69 by the intermediary of ball and socket joints. By this connection the function of the roller pair 21, 22 is made interdependent with that of the roller pair 19, 20, inasmuch as by the described mechanisms on the roller 19 swinging about the shaft 26 in upward direction the roller 21 is coupled-in and is rotated, and on the roller 19 swinging downwardly the roller 21 will be uncoupled and arrested.

If now the work piece S, into which a small incision is previously made by hand, is led through between the gate members 16, 17 against the knives 5, 6, the waste portion S' being fed in between the rollers 19, 20 and the embroidered portion S'' between the rollers 21, 22, there will be exerted a pull on the portion S' by the ascending embroidery edge K' of the festoon F (Fig. 7) offering relative strong resistance to the cutting, with the result that the roller pair 19, 20 will swing upwardly. As a consequence the coupling members for the roller 21 are actuated which causes the rollers 21 and 22 to rotate and draw taut the fabric portion S'', while by reason of the braking action exerted by spring 36 on the upswinging roller 19, the roller pair 19, 20 rotates more slowly, which means a lessened pull on the

fabric portion S''. The fabric is drawn against the knives by the roller pair 21, 22 until the descending edge K'' of the embroidery is about to be cut, the resistance offered by the edge being low and only a correspondingly weak pull being exerted on the fabric portion S', so that the roller pair 19, 20 swings down, when simultaneously the roller pair 21, 22 will be uncoupled and the fabric is once more drawn up against the knives by the now speeding-up roller pair 19, 20 until the ascending edge K' of the succeeding festoon F contacts with the knives. The control of the roller drive, thus, always depends upon the direction of the embroidery edge just being cut, with the conformation of the latter being immaterial since the described change can be repeated over and over.

20 What I claim is:—

1. In a machine for cutting fabric along an embroidered edge, a pair of partly overlapping, oppositely revoluble disk knives arranged to cut the fabric, feed rollers for 25 the fabric, and means in connection with said disk knives for controlling the operation of said feed rollers in accordance with the varying cutting resistance.

2. In a machine for cutting fabric along 30 an embroidered edge, superimposed oppositely revoluble disk knives partly overlapping one another in close contact with their peripheries forming a cutting point, relatively adjustable gate members in front 35 of the cutting point and forming an intake slit for the ground fabric, rollers for automatically controllably feeding the work piece, means for interdependently actuating said rollers in accordance with the varying

degree of resistance offered to said cutting 40 knives by the work material.

3. In a machine for cutting fabric along an embroidered edge, two superimposed oppositely revoluble disk knives coacting to form a cutting point, pairs of rollers for feeding the work piece to the cutter, one of said pairs being mounted in front and the other back of said cutter, means for interdependently actuating said rollers in accordance with the varying degree of resistance offered to said cutting knives by the work material, an outrigger member on which the front pairs of rollers is mounted, a shaft on which the outrigger member is journaled, and a driving gear on said shaft 50 whereby the outrigger member may swing about said shaft.

4. In a machine for cutting fabric along an embroidered edge, two superimposed oppositely revoluble disk knives coacting to form a cutting point, pairs of rollers for feeding the work piece to the cutter, one of said pairs being mounted in front and the other back of said cutter, means for interdependently actuating said rollers in accordance with the varying degree of resistance offered to said cutting knives by the work material, an outrigger member on which the front pairs of rollers is mounted, a shaft on which the outrigger member is 65 journaled, a driving gear on said shaft whereby the outrigger member may swing about said shaft, a spring exerting influence on one of the said front rollers, and an obliquely journaled and laterally displaceable leader arm operatively connected to 70 said spring.

ALOIS TSCHERNE.
